NATHANIEL D. PONNAY, OF LOS ANGELES, CALIFORNIA.

PRINTING-PRESS GAGE.

1,367,091.

Specification of Letters Patent.

Patented Feb. 1, 1921.

Application filed January 26, 1920. Serial No. 354,316.

To all whom it may concern:

Be it known that I, NATHANIEL D. PONNAY, a citizen of the United States, residing at Los Angeles, in the county of Los Angeles 5 and State of California, have invented new and useful Improvements in Printing-Press Gages, of which the following is a specification.

This invention relates to printing apparatus and more particularly to paper gages attachable to the platens of printing presses, and has for its object to provide a paper gage which can be applied with facility to the platen and that can be independently adjusted at the requisite angle as may be required to conform to the alinement of the form on the press bed, and further has for its object to provide a device that is simple, substantial, practicable and inexpensive and 15 consists of the construction embodiments of which are illustrated in the accompanying drawings and described and claimed herein.

Figure 1 is a perspective of a platen with the improved gages applied.

Fig. 2 is a perspective of a platen showing the draw sheet slotted to receive the gages.

Fig. 3 is a perspective showing a set of gages of modified construction.

Fig. 4 is a plan view of the improved gage on a scale about 4 to 1 of the actual size.

Fig. 5 is a rear edge view of the gage in Fig. 4.

Fig. 6 is a front edge view of the gage with the finger in section.

Fig. 7 is a section on line 7—7 of Fig. 4.

Fig. 8 is a section on line 8—8 of Fig. 4.

Fig. 9 is an underneath perspective of the top cap of the gage.

Fig. 10 is a plan view of the bottom plate of the gage.

Fig. 11 is an edge view of the plate shown in Fig. 10.

Fig. 12 is a perspective of the gage showing a modified form of finger.

Fig. 13 is a perspective of a modified and preferred form of the invention; Fig. 14 is a perspective of the gage with the clamp nut removed; Fig. 15 is a perspective of the guide finger detached; Fig. 16 is a plan view of the modified form; Fig. 17 is an edge view looking at the left end of Fig. 16; Fig. 18 is a section on line 18—18 of Fig. 16; Fig. 19 is a sectional view on line 19—19 of Fig. 16.

The invention consists essentially of a bottom member or plate 2 made of suitable material, preferably metal, rather thin in proportion to its length and width and having its front transverse edge beveled at 3 60 and its rear edge beveled at 4 upwardly and rearwardly to facilitate the attachment of the gage to the usual draw sheet S, shown in Figs. 1, 2 and 8 as applied to the platen P and secured by the usual foldable clips C. 65

The bottom member 2 is provided with a fixed central upwardly extending stud 5 of suitable proportions having a reduced neck or annular groove 6 above which the stud is threaded as at 7 to receive the clamping 70 nut 8. This nut is designed to press a suitable clamp block or cap 10, Fig. 9, downwardly so as to bite upon and engage the inserted portion of the draw sheet S when the bottom plate or member 2 has been mounted 75 upon the draw sheet, as clearly shown in Figs. 1 and 8. The draw sheet is perforated at suitable locations by pairs of parallel slits 11 spaced apart sufficiently to permit the introduction of the gage bottom plate 2 80 so that it will be overlapped by the edges of the sheet S parallel to the opposite sides of the slits, the body of the plate 2 overlying the central free portion 12 of the strip or sheet.

The cap block 10 is substantially plane in its upper surface and its lower face is longitudinally channeled as at 13 forming a series of parallel body portions 14, the front ends of which form downwardly extending supporting parts 15 to rest upon the adjacent upper face of the bottom 2, and the block 10 is riveted or otherwise attached to the plate 2 as by rivets 16 passing through apertures 17 in the cap and plate members. 95

That portion of the cap block to the rear of the supporting parts 15 provides a resilient tongue or plate that overlies the central portion of the base plate and which resilient tongue is pressed downwardly when nut 8 100 is rotated so that it moves downward upon stud 5.

The rear ends of the body portions 14 are shown as toothed at 18 to coöperate with the toothed portion 19 on the upper face of 105 the plate 2, so that when the cap 10 has been applied, as above described, with the threaded part 7 of the stud 5 extending upwardly through an aperture 20 provided for its reception in the cap 10; then after the plate 110

2 has been inserted beneath the draw sheet S and pressed rearwardly so that a portion of the sheet passes between the relatively spaced teeth 18 and 19, then when the clamp 5 nut 8 is turned down on the screw 7, the resilient rear portion of the plate 10 is flexed downwardly the inserted portion of the draw sheet is firmly clamped between said teeth and thus the gage is held firmly in position. It will be seen that this permits the relative angular adjustment of the gage upon the sheet S as may be desired to conform with alinement of the type form mounted in the press.

15 To facilitate the guiding of the sheet or blank B to be printed into position and adjustment upon the several gages that may have been mounted on the draw sheet S each of the gages is provided with a forwardly 20 extending and removable finger 25 of suitable contour, the finger being in the form of a hair-pin and its spaced ends insertible into the channels 13 in the lower face of the cap 10, the inner surfaces of the arms of 25 the fingers 25 passing into the grooved portion 6 of the stud 5 and being clamped securely thereon when the clamp nut 8 is advanced on the screw 7.

Preferably, the guide finger 25 is bowed 30 outwardly and upwardly, as plainly shown in Fig. 8, so that the edge of the paper will pass freely between the outer end of the finger and the adjacent surface of the draw sheet which overlaps the inserted end 35 of the bottom 2 of the gage.

There is shown in Fig. 12 a slightly modified form of bowed finger in which case the outermost end of the finger is deflected upwardly as at 25' to permit the ready insertion 40 of the edge of the paper, and then somewhat to the rear of the end 25 of the finger is bowed upwardly as at 25^a this forming a spring structure normally pressing the finger end 25' downwardly on to the draw 45 sheet S to facilitate in holding the paper snugly down on the platen.

A simple and preferred embodiment of the invention is illustrated in Figs. 14 to 50 inclusive wherein the gage is shown as made up of one integral piece of sheet material of suitable length and width, the sheet forming a bottom 30 of suitable dimensions at one end of which the metal is doubled upon itself as at 31 and thence is provided 55 with an upwardly extending shoulder 32 forming the stop surface, as seen in Fig. 19, for the inserted sheet B to be printed upon. The sheet is continued rearwardly from the shoulder 32 in a plane substantially 60 parallel to the bottom plate or portion 30 and forms the top 33 extending rearwardly to a suitable distance and provided with a downwardly turned lip 34 beneath which the draw sheet S is inserted, as in Fig. 19, to 65 overlap the adjacent portion of the base 30.

Intermediately the length of the top 33 between the shoulder 32 and the lip 34 there extends upwardly a screw 35 suitably secured on the upper surface of the bottom 30 so as to project through an aperture 36 provided therefor in the top 33, this screw being designed to receive a clamp nut 37 which when turned down presses upon the yielding leaf 33 so as to cause the lip 34 to bind upon and hold the inserted portion of the draw 75 sheet S.

The guide finger 25 is designed to be clamped beneath the clamp nut 37 in the same manner as described relative to the form shown in Fig. 8, but in modified form 80 the top or yielding leaf 33 is formed with depressed portions as grooves 38 extending parallel and into which the arms of the finger 25 can be inserted so as to be engaged by the lower face of the clamp nut 37. 85

Various changes may be made without departing from the spirit of my invention as claimed.

I claim:

1. In a printing press gage, a base plate, 90 a stud seated in and projecting upwardly therefrom, a top plate rigidly fixed at one end of said base plate to one side of said stud, which top plate is perforated to receive the stud, a nut seated on the threaded 95 upper end of the stud, the under side of the top plate being slotted to receive the legs of a paper guiding finger, and parts of the top surface of the base plate and adjacent parts of the under surface of the top plate being 100 corrugated in order to firmly clamp an interposed sheet.

2. In a printing press gage, a base plate, a stud seated in and projecting upwardly therefrom, a top plate rigidly fixed at one 105 end of said base plate to one side of said stud, which top plate is perforated to receive the stud, a nut seated on the threaded upper end of the stud, the under side of the top plate being slotted to receive the legs of a paper guiding finger, said stud being provided with an annular groove for the reception of the legs of said paper guiding finger, and parts of the top surface of the base plate and adjacent parts of the under 115 surface of the top plate being corrugated in order to firmly clamp an interposed sheet.

3. In a printing press gage, a base plate, a top plate rigidly fixed at one end to said base plate, said top plate having a resilient portion that is spaced apart from the base plate, clamping means co-operating with said base plate and the resilient portion of the top plate, and parts of the under surface of the resilient portion of the top plate 120 and adjacent parts of the top surface of the base plate being corrugated in order to grip an interposed sheet.

4. In a printing press gage, a base plate, a top plate rigidly fixed at one end to said 125

- base plate, said top plate having a resilient portion that is spaced apart from the base plate, clamping means coöperating with said base plate and the resilient portion of the top plate, the under side of the top plate being slotted, and a bifurcated paper guiding finger having its legs positioned in the slots in said top plate.
5. In a printing press gage, a base plate, a resilient clamping plate fixed on top of said base plate, a stud seated in the base plate and passing through the top plate, a nut mounted on the threaded upper end of said stud, said stud being provided with an annular groove below the top plate, and a bifurcated paper guiding finger having its legs positioned in the annular groove in said stud.
6. In a printing press gage, a base plate, a slotted resilient plate fixed on said base plate, means coöperating with said plates for causing them to grip an interposed sheet, and a bifurcated paper guiding finger having its legs positioned in the slots of the resilient plate.
7. In a printing press gage, a base plate having a portion of its surface corrugated, a resilient top plate secured at one end to said base plate, the main body portion of which top plate overlies the corrugated portion of the base plate, parts of the under surface of the overlying portion of said top plate being corrugated, and means for moving the overlying portion of the top plate toward the base plate to grip an interposed sheet between the corrugated surfaces of said base and top plates.
8. In a printing press gage, a base plate having a portion of its surface corrugated, a resilient top plate secured at one end to said base plate, the main body portion of which top plate overlies the corrugated portion of the base plate, parts of the under surface of the overlying portion of said top plate being corrugated and the under side of said top plate being provided with slots, and a bifurcated paper guiding finger having its legs positioned in said slots.

In testimony whereof I have signed my name to this specification.

NATHANIEL D. PONNAY.
